UNITED STATES PATENT OFFICE.

WILLIS DE GROFF WILCOX, OF CHICAGO, ILLINOIS.

COMBINED SPRING AND FRICTION DRAFT-GEAR.

932,215.

Specification of Letters Patent. Patented Aug. 24, 1909.

Application filed July 5, 1907, Serial No. 382,283. Renewed February 11, 1909. Serial No. 477,452.

To all whom it may concern:

Be it known that I, WILLIS DE GROFF WILCOX, a citizen of the United States, residing at Chicago, in the county of Cook and State of Illinois, have invented certain new and useful Improvements in Combined Spring and Friction Draft-Gear, of which the following is a specification.

This invention relates more particularly to a draft gear for use on railway cars in connection with the draw bar of a coupling.

The object of the present invention is to provide mechanism adapted to cushion the draft bar when shocks are imparted thereto in either direction.

A further object of the invention is to combine the entire mechanism into an integral structure adapted to be positioned and secured beneath the body of the car without difficulty and without the necessity for building the structure into the car.

A further object of the invention is to so arrange the spring mechanism that a maximum of efficiency will be secured in a minimum of space and so that the spring action will be equally distributed throughout the entire cushion and uniformly exerted at all points thereof.

The invention relates to the device as a whole and to the method of mounting and securing it beneath the car body, and to the features of construction and combination of parts hereinafter described and claimed.

In the drawings, Figure 1 is a side elevation of the draft gear of the present invention, with the draft bar and coupling head secured thereto; Fig. 2 a cross sectional view of the same, somewhat enlarged, taken on line 2—2 of Fig. 1; Fig. 3 a sectional plan view of the draft gear uncompressed; Fig. 4 a similar view showing the draft gear compressed by a forward pull or tension on the draft bar; Fig. 5 a cross sectional view of the draft gear in normal position; Fig. 6 a similar view showing the parts in compressed position; Fig. 7 a plan view of one of the wedge caps; Fig. 8 a plan view of one of the friction blocks; Fig. 9 an end view of the same; and Fig. 10 a side elevation of the same.

The draft gear comprises a substantially rectangular casing 11, provided in its ends with vertically elongated openings 12, for the projection therethrough of wedge caps 13. Each of the wedge caps comprises a rectangular head 14 and an inwardly tapering body

portion 15, best shown in Fig. 7. The wedge shaped body portion is cut away to provide a central recess 16, on each side of which are converging ribs 17, one on each side of the wedge cap. The wedge caps are designed to coöperate with a pair of friction blocks 18, each of which comprises a base plate 19, flat on its under face, which base plate has upwardly extending along each side thereof a wall 20 having a flat top face 21 and sloping end faces 22, each of which is provided with a groove or channel 23 adapted to coöperate with one of the sloping ribs 17 of the wedge cap. The space 24 intermediate the sloping walls is of concave formation and is bridged, in its center, by a cross rib 25, the side walls being cut away to provide recesses 26 in register with the rib 25, which arrangement provides, in effect, a transversely extending socket 75 which is adapted to receive a square hollow key 27, which, when the parts are assembled, will extend vertically through the boxlike casing and between the friction blocks, which, when in normal position, lie in contact with one another. The hollows 24 are of substantially semi-cylindrical formation, so that when the two coöperating friction blocks are placed in register with one another a pair of substantially cylindrical recesses or chambers 85 will be afforded, one on each side of the dividing rib or ridge 25, which chambers are adapted to receive a pair of coil springs 28, the inner ends of which abut against circular disk washers 29, each of which is provided on its inner face with a stud 30, which is entered into the adjacent wall of the square key bar 27, and each of the washers is provided, on its outer surface, with a boss 31, which is surrounded by the inner end of a coil spring. 95 The outer ends of the coil springs pass through the recesses or holes 16 between the tapered sides of the wedge caps, and the end of each spring abuts against the inner face of the head 14 of the wedge cap, the grooves of 100 which will, when the parts are assembled, enter the corresponding channels of the friction blocks.

Between each of the flat outer faces of the wedge blocks and the adjacent wall of the 105 casing are interposed a plurality of concavo-convex spring plates 32, which extend from end to end of the box or casing and are positioned with their convex sides to the center, the innermost one of the plates being in contact with the flat surface of the adjacent friction block. 110

Surrounding the box or casing of the draft gear is a yoke 33 having top and bottom rails 34, which lie in close contact with the top and bottom walls of the box or casing, and the top and bottom rails are connected by means of a cross head 35, which abuts against a transversely elongated rear follower 36, which in turn abuts against the head end of one of the wedge caps, which, when the parts are in normal position, project outwardly from the ends of the box or casing, as shown in Fig. 3. The upper and lower rails of the yoke, at the forward end, terminate in attaching ears 37, which are offset with respect to the rails and afford shoulders or abutments 38, between which and the head of the forward wedge cap is interposed a forward follower 39 similar in all respects to the follower 36. The followers 36 and 39 project laterally beyond the side walls of the box or casing and rest upon a pair of supporting guideways 40, each of which is provided, at each end, with an upturned shoulder or abutment 41, which in turn terminates in an attaching tongue or flange 42, which is secured to the under face of a longitudinally extending X beam 43 of the car body. Interposed between the ears 37 is the end of a draw bar 45, which is secured to the yoke by means of a pivot pin 46, the forward end of the draw bar being provided with a coupler head 47 of the usual character.

In use when the draft gear is in normal position, as shown in Fig. 3, the coil springs will be distended and the heads of the wedge caps projected, which projection holds the forward and rear followers into close engagement with the shoulders or abutments 41 of the supporting guide rails. When the draft gear is subjected to a pulling strain the cross head of the yoke, bearing against the rear follower, will pull the follower forward against the tension of the coil and flat springs until both of the coil springs have been compressed to their limit of compression and the heads of the wedge caps lie flush with the ends of the box or casing. This movement will carry the box or casing forwardly along the guide rails, upon which it rests until the parts have assumed the position shown in Fig. 4. The pull on the draw bar equally distributes the compressing force in both ends of the draft gear, the action and reaction being the same and in opposite directions. These opposite forces compress both of the wedge caps equally and force out the opposite ends of the friction blocks against the tension of the curved spring plates interposed between the wedge blocks and the sides of the casing. At the same time the friction of the wedge caps against the friction blocks will be very great, and this friction, combined with the resulting tension of the coil and plate springs, gives a very high degree of efficiency to the draft gear.

The plate springs, by reason of the fact that they extend from end to end of the casing, give a maximum degree of efficiency, especially in view of the fact that the springs are contacted, from end to end, by the flat surface of the adjacent friction block, so that the compressing action exerted against the springs will be equally distributed from end to end thereof and not concentrated at a single point, as has been the faulty practice in certain prior constructions. The distending action of the wedge caps being equal at both ends of the friction blocks, the latter will be outwardly moved in a straight line, which brings an equal pressure to bear simultaneously at all points on the inwardly curved plate springs. The draft gear, being inclosed in a casing of the character indicated, is in the form of a complete, integral structure, which can be applied to or removed from a car without building the structure into the car, which is an inconvenient and imperfect method of applying draft gear to cars.

What I regard as new and desire to secure by Letters Patent is:

1. A draft gear comprising a casing, two oppositely disposed friction blocks having inwardly sloping acting faces, oppositely disposed tapered wedge caps cooperating with the friction blocks and outwardly projecting from the ends of the casing when in normal position, spring mechanism acting directly against the wedge caps, springs interposed between the friction blocks and the adjacent walls of the casing, a yoke surrounding the casing, front and rear followers bearing against the wedge caps and adapted to be actuated by the yoke, and abutments for limiting the movements of the followers, substantially as described.

2. A draft gear comprising a box shaped casing, friction blocks extending from end to end of the casing and provided with flat upper bearing faces, plate springs extending from end to end of the casing and interposed between the bearing faces of the friction blocks and the adjacent side walls of the casing, a pair of wedge caps normally extending outwardly from the ends of the casing and cooperating with the friction blocks, and coil spring mechanism bearing against the wedge caps, substantially as described.

3. A draft gear comprising a box shaped casing, friction blocks extending from end to end of the casing and provided with flat upper bearing faces, concavo-convex plate springs concavo-convex in transverse section and extending from end to end of the casing and interposed between the bearing faces of the friction blocks and the adjacent side walls of the casing, a pair of wedge caps normally extending outwardly from the ends of the casing and cooperating with the friction blocks, and coil spring mechanism bear-

ing against the wedge caps, substantially as described.

4. A draft gear comprising a box shaped casing, friction blocks extending longitudinally of the casing, plate springs concavo-convex in cross section and extending longitudinally of the casing and interposed between the friction blocks and the adjacent side walls of the casing, a pair of wedge caps

normally extending outwardly from the ends 10 of the casing and coöperating with the friction blocks, and spring mechanism bearing against the wedge caps, substantially as described.
